Howson and Howson

UNITED STATES PATENT OFFICE

ALWIN VON AUW, OF BROOKLYN, NEW YORK, ASSIGNOR TO BOORUM & PEASE COMPANY, OF NEW YORK, N. Y., A CORPORATION OF NEW YORK

VISIBLE INDEX

Application filed May 17, 1928. Serial No. 278,587.

This invention relates to the overlapping type of visible index card having a hinged ⁵ sliding mounting and is in the nature of an improvement upon cards having ears outside the body of the card at either side and parallel to those sides.

One object of this invention is to provide a card adapted for rapid and accurate inter-engagement with similar cards to produce a ¹⁰ visible index, another object of the invention being to provide a form of card which will engage the adjacent card positively. Other objects will be made plain as the cards are described.

¹⁵ In the drawings—

Figure 1 is a plan view of a card made according to my invention,

Fig. 2 is a plan view of part of a panel showing a number of my cards mounted ²⁰ thereon;

Fig. 3 is an exaggerated longitudinal section, taken on the line 3—3 of Fig. 2, looking in the direction of the arrow;

Fig. 4 is a perspective view of the corners ²⁵ of several cards interengaged with each other but not yet inserted in the panel, while

Fig. 5 is an edge view of one of my new cards.

According to my invention the cards ³⁰ 12 are adapted to be interengaged with each other and to be mounted in a panel in hinged relation in a manner similar to that shown and described in my United States Patent No. 1,649,763 dated November 15th, 1927, in which lateral depending ears form the suspending and spacing means. As set forth in that patent, the card may conveniently be hinged, preferably on a line with, or just below a line joining the upper ends of the incisions between the depending lobes of the ears and the free side edges 13 of the card.

Making the ears and the upper part 19 of the card integral with the record portion 16 of the card, is optional. I have found that ⁴⁰ in the assembling of the cards, the depend-

ing ears 14 sometimes get on top of the adjacent card, thus destroying the straddle of that card on its neighbor, and causing loss of the overlap. To facilitate the card's always engaging the adjacent card in the necessary straddled manner, I propose to give the lower lobe 17 of the ear 14 a permanent bend which will make it lie at an angle dorsal or posterior to the body of the card as illustrated particularly in Figs. 3, 4 and 5.

This permanent backward bend of the depending lobe 17 can be obtained if desired by hot-pressing the card at the time the card is being manufactured.

To further insure the depending ear's finding its way under the ear of the card below, I sometimes find it convenient to make the ear 14 with an upper lobe 24 and to give this upper lobe a permanent bend which will make it lie at an angle ventral or anterior to the body of the card (Fig. 5).

This permanent ventral bend of the upper lobe 24 may be obtained by hot pressing the card at the time the card is being manufactured.

⁷⁰ As will be seen from Fig. 4, when a card is inserted at the top of a column, the dorsally bent lower lobe of the depending ear of the card being inserted, will easily and automatically slide under the ventrally bent upper lobe of the former top card of the column.

Similarly when a card is being inserted at the bottom of the column, the ventral angle of the upper lobe of the new card, will automatically slide up over the dorsally bent depending lobe of the ear of the former bottom card.

Likewise when the cards are in a panel 10, and a new card is to be inserted into the middle of a column, the two cards between which it is to be inserted are separated to a distance about equal to the overlap between the cards, then one ear is inserted under its corresponding flange 11 of the panel. The depressed depending tip 35 of the lower lobe 17 will automatically slide under the up-

turned upper lobe 24 of the card below, while the upturned upper lobe of the card being inserted will automatically ride up over the depressed depending lower lobe of the card already in the panel above the card being inserted. Then the card being inserted is flexed in the middle, and the other ear inserted under the other flange with similar result.

The upper lobe 24 of the ear may be formed by making the slight notch 23 at the point of junction of the ear to the top 19 of the body of the card. The ventral bend is preferably given only to the upper lobe 24 of the ear, and not to the top 19 of the card, for it is desirable that the bodies of the cards lie flatly upon the panel, to give a flat working surface.

It is desirable that the card be notched only very slightly at 23, so that there will be no deep nesting between the cards. A notch of say $\frac{1}{16}$ of an inch or less will provide an ample upper lobe to be given the desired ventral angle, but will not cause inconvenient nesting.

Fig. 3 is termed exaggerated, because in normal position the record portion 16 of each card would tend to lie practically in the same plane as the top 19, instead of meeting 19 at an arc, as shown in this figure. The figure is drawn to show more clearly the relative positions of the ventrally bent upper lobes and dorsally bent lower lobes when a number of cards are interengaged with each other.

I claim:

1. A visible index card comprising a body portion in combination with an ear having a depending lobe at either side of said body portion adjacent to the upper edge, the lower tip of said ears being bent at an angle dorsal to the body of the card.

2. A visible index card comprising a body portion in combination with an ear having a depending lobe at either side of said body portion adjacent to the upper edge, the lower tip of said ears being hot-pressed to lie dorsal to the body of the card.

3. A visible index comprising a panel having inwardly facing opposed flanges in combination with a series of overlapping cards each comprising a body portion overlying the body portion of the card below and an ear having a depending lobe at each side of the body portion adjacent to its upper edge underlying the corresponding flange and the ear of the card below, the lower tip of each ear being permanently bent at an angle dorsal to the body of the card, the body portion being hinged on a line joining the points of severance between the body portion and the depending lobes of the ears.

4. A visible index card comprising a body portion in combination with an ear at either side of said body portion adjacent to the upper edge, said body portion being hinged on a line reaching from one free side edge of said

body portion to the other, each ear having an upper lobe and a depending lower lobe, said upper lobe being bent to lie at an angle ventral to the body portion of the card, and the tip of the lower lobe being bent to lie at an angle dorsal to said body portion.

5. A visible index card made of one integral piece of sheet material comprising a body portion in combination with an ear having a depending lobe on either side of said body portion adjacent to the upper edge, said ears being separated from the body portion below the juncture between said body portion and said ears, and being slightly separated from said body portion above the juncture between said body and said ears, the upper tip of said ears being pressed to lie ventral to the body of the card and the lower tip being pressed to lie dorsal to the body of the card.

6. A visible index card made of one integral piece of sheet material comprising a body portion in combination with an ear on either side of said body portion adjacent to the upper edge, said ears having an upper lobe and a depending lower lobe, said upper lobe being hot-pressed to lie at an angle ventral to the body portion of the card, and the tip of the lower lobe being hot-pressed to lie at an angle dorsal to said body portion.

7. A visible index card comprising a body portion in combination with suspending and spacing means outside said body portion comprising an ear joined thereto on each side adjacent the upper edge thereof, each ear having a downwardly hanging lobe, said body portion being hinged on a line joining the points of severance between the body portion and the downwardly hanging lobes of the ears, said ears having upper lobes above the hinge line and lateral to the body portion, said upper lobes being pressed to lie at an angle ventral to the body portion and the tips of said downwardly hanging lobes being pressed to lie at an angle dorsal to the body portion of the card.

8. A visible index comprising a panel having inwardly facing opposed flanges in combination with a series of overlapping hinged cards each comprising a body portion overlying the body portion of the card below and an ear at each side of the body portion adjacent to its upper edge and underlying the corresponding flange said ears having an upper lobe formed to lie at an angle ventral to the body portion of the card, and a depending lower lobe having its tip formed to lie at an angle dorsal to said body portion, each lower lobe underlying the ear of the card below.

9. A visible index comprising a panel having inwardly facing opposed flanges in combination with a series of overlapping cards each comprising a body portion overlying the body portion of the card below and an ear at each side of the body portion adjacent to its upper

edge said ear having a depending lobe underlying the corresponding flange and the ear of the card below, said ears being slightly separated above the juncture between the body and ears to form an upper lobe, said upper lobe being permanently pressed to lie ventral to the body of the card and the tip of the depending lobe being permanently pressed to lie dorsal to the body of the card.

10 In testimony whereof I have signed by name to this specification.

ALWIN VON AUW.
